METHOD OF MAKING INFLATED BALLS

Benjamin J. Axton, Jr., Holyoke, Mass., assignor to A. G. Spalding & Bros. Inc., Chicopee, Mass., a corporation of Delaware

Original application September 22, 1950, Serial No. 186,214. Divided and this application August 10, 1951, Serial No. 241,287

6 Claims. (Cl. 154—16)

The present invention relates to the method of making inflated balls and particularly inflated balls having a molded casing completely enclosed in the bladder and provided with a slit extending partially through the casing, which slit is closed by a separate lace and to the method of making the same, and is a division of my application Serial No. 186,214, filed September 22, 1950.

The present invention is applicable to all types of inflated balls, such as basketballs, soccer balls, volley balls and footballs. However, it is particularly well suited for footballs in which the lace in the casing provides a means whereby the ball may be gripped for passing or handling.

In sewn footballs it has been the practice to leave a portion of one of the seams open and to insert the bladder through this seam and close the same by a flap and a lace extending across the opening. This has the disadvantage, however, that the casing is weakened at the opening and has a tendency to bulge after long use. In an effort to overcome this tendency unsewn balls were made up employing a laminated casing but no means were provided for receiving the lace, but instead a simulated lace was molded into the surface of the ball. This, however, did not provide a proper or satisfactory gripping action.

The present invention has the advantage of the unsewn ball insofar as maintaining its shape is concerned and the advantages of the sewn ball in that the separate lace provides for adequate gripping.

In carrying out the method of the present invention a plurality of panels of fabric are provided with adhesive coatings and are laid up on the ball to provide a multiply casing. Incorporated in the wall of the casing is an adhesion resistant substance which prevents, in a zone in the wall, adhesion between adjacent plies to form a pocket therebetween. The outer plies of the casing overlying the pocket are slit and punched and a lace is inserted to draw the edges of the slit together. With this structure it will be seen that the ball will maintain its original shape and will resist distortion at the slit because of the underlying fabric forming part of the wall of the casing while at the same time the lace which is inserted in the holes in the outer plies of the casing will provide an adequate grip for passing or otherwise handling the ball.

In forming the pocket in the casing, in the illustrated form of the invention, a patch is used having an adhesive coated fabric as its base, an adhesion resistant portion lying within the edges of the fabric on one face thereof and an anvil lying within the edges of the adhesive resistant area. This patch is located on the ball so as to lie within the edges of the panels forming the wall so that when a slit is formed in the casing over the anvil it will not pass through a seam in the fabric forming the multiply wall of the casing.

The ball of the present invention may have a rubber cover formed with the exterior surface molded to simulate a leather ball or may be provided with a rubber cover having raised seams between which panels of leather may be inserted in the manner described in the Reach patent No. 2,182,052, issued December 5, 1939.

A feature of the present invention is the making of a ball so that the casing may be built up and the slit provided in the adhered-together outer plies of the casing without destroying the shape-sustaining properties of the casing.

Other features and advantages of the invention will be

2

apparent from the specification and claims when considered in connection with the drawings in which:

Figure 1 shows a side elevation of a football with the lace in place.

Fig. 2 is a perspective of the ball with the lace removed.

Fig. 3 is a sectional view of the ball through the patch and before molding.

Fig. 4 is a view of the ball of Fig. 3 after the molding operation with the rubber coating on the outside and the slit and holes therein.

Fig. 5 is a plan view of the patch.

Fig. 6 is a view similar to Fig. 3 of another form of the invention.

Fig. 7 is a view of the ball of Fig. 6 after the molding operation with the rubber coating on the outside and the slit and holes therein.

In the illustrated form of the invention the ball comprises an outer molded surface 10 to simulate a pebbled leather. It is also provided with molded seams 11 with simulated stitches therein and simulated stitches 12 on the surface.

In forming the ball of Fig. 1 a bladder 13 having a valve 14 is laid thereon the usual panels of fabric coated 25

on their faces with adhesive material such as rubber cement, to form two plies 15, 16 completely enclosing the bladder. At a zone to one side of the valve, as shown in Fig. 2, there is then placed a patch. The patch, as shown in detail in Fig. 5, comprises a layer of fabric 17 having 30

adhesive on both sides. Overlying one face of the patch is an area of adhesion resistant material 18. The adhesion resistant material, in the preferred form of the invention, comprises a thin sheet of polyethylene or the like thermoplastic which during the molding operation forms a coating 35

on the adjacent surfaces and prevents them from adhering. It is to be understood, however, that other sheet material such as fabric, paper or the like treated to prevent adhesion of the fabric in the zone may be used. If desired, a coating of a suitable adhesion resistant material 40

may be used in place of the sheet material. An example of such a coating would be a lacquer formed of polyethylene or the like thermoplastic which is applied to the one face of the patch. In the center of the adhesion resistant material is an anvil 19. The anvil, in the preferred form of the invention, comprises a sheet of aluminum foil. If desired, however, it may be a thin plate of steel or other material capable of forming a surface against which the cutting tool can operate in forming the slit without cutting the inner plies.

50 After the patch is put in place it is covered by panels forming at least one layer or ply 20. The whole casing is then covered with a layer of rubber 21 and placed in a suitable mold (not shown) where, under suitable heat and pressure, the plies of the casing and the rubber 55

of the cover become united into a homogeneous mass.

During the molding operation the adhesion resistant material and the anvil prevent the patch from adhering to the adjacent ply so as to form a pocket therebetween. The cover and outer plies of the casing are then provided with a slit 22, as indicated by the heavy line in

60 Fig. 4, in the zone overlying the anvil by passing a sharp instrument through the adhered outer plies, the anvil preventing the instrument from cutting the inner plies. The adhesion resistant material, it will be noted, 65

extends beyond the sides of the anvil so that the pocket formed thereby will provide for movement of the anvil and enable it to be removed through the slit. The pocket is indicated by the heavy black line 23 in Fig. 4. After the anvil is removed, holes 24 are punched along each

70 side of the slit 22 and through which a lace 25 is inserted as shown in Fig. 1 to draw the sides of the slit together. The lace can be a strip of natural or imitation leather, flexible plastic or fabric as required.

75 It will be seen from Fig. 4 that the portion of the casing underlying the slit is joined to the outer plies all around the pocket and is of a size as determined by the outer plies and hence will prevent the casing from bulging at the slit while the outer plies will provide satisfactory means for receiving the lacing. In the preferred

80 form of the invention the valve is located remote from

the pocket and slit, so that fabric under the slit is continuous and presents a maximum of strength.

The form of the invention shown in Figs. 6 and 7 is generally similar to that shown in the preceding figures with the exception that in this form of the invention the patch is first laid on the bladder at a zone remote from the valve with the back of the fabric base 17 engaging the bladder and the adhesive resistant layer 18a and anvil 19a facing upwardly. The panels are then laid on to form several plies 15, 16, 20 of fabric thereover as shown in Fig. 6. The rubber cover 21 is applied and assembly molded as explained in connection with Figs. 1-5. The slit 22a, as indicated by the heavy line in Fig. 7, is made therein at the zone over the anvil through the three outer plies and cover, the inner ply being formed by the fabric of the patch. The anvil is removed from the pocket 23 indicated by the heavy line in Fig. 7 and lace-receiving holes 24 are punched on either side of the slit. The lace is then inserted into the holes in a manner similar to that shown in Fig. 1.

It will be seen from the procedures outlined above that I have provided a novel method for making the ball wherein a multiply molded casing is formed having a pocket therein and a slit is cut in the casing to extend partially through the casing into the pocket and holes are punched in the casing adjacent the slit to receive the lace so that a ball having the desirable characteristics of a molded ball and a sewn ball having a laced opening are achieved.

While in the specific forms of the invention I have disclosed the use of a rubber cover, it is to be understood that if desired a leather cover may be applied on the ball by providing in lieu of the rubber cover a thin rubber layer having raised ridges thereon defining leather panel-receiving spaces as described in the aforementioned Reach patent.

Variations and modifications may be made within the scope of the claims and portions of the improvements may be used without others.

I claim:

1. The method of forming an inflated ball having a bladder provided with a valve, the steps of laying on the bladder a plurality of plies of fabric having adhesive thereon to form a casing therearound and including between the plies, at a zone remote from said valve, a layer of adhesion resistant material and an anvil plate; enclosing the casing in a layer of rubber; placing the ball in a mold and subjecting the ball to heat and pressure to adhere the plies and layer of rubber together and to form the required surface configuration on the rubber layer, the layer of adhesion resistant material and anvil plate preventing the adjacent plies in said zone from adhering together; removing the ball from the mold and cutting a slit in said zone through the adhered outer plies and layer of rubber to said anvil; removing the anvil; punching a row of holes in the outer plies on each side of the slit; and inserting a lace through the holes to draw the sides of the slit together.

2. The method of forming an inflated ball having a bladder provided with a valve, the steps of laying on the bladder a plurality of plies of fabric having adhesive thereon to form a casing therearound and including, at a zone remote from said valve, a layer of adhesion resistant material and an anvil plate; placing the ball in a mold and subjecting the ball to heat and pressure to adhere the plies together, the layer of adhesion resistant material and anvil plate preventing the adjacent plies in said zone from adhering together; removing the ball from the mold and cutting a slit in said zone through the adhered outer plies to said anvil; removing the anvil; punching a row of holes in the outer plies on each side of the slit; and inserting a lace through the holes to draw the sides of the slit together.

3. The method of forming an inflated ball having a bladder provided with a valve, the steps of laying on the bladder a plurality of plies of fabric having adhesive thereon to form a casing therearound; interposing between the plies of fabric, at a zone remote from said valve, pocket-forming means including an anvil plate; placing the ball in a mold and subjecting the ball to

heat and pressure to adhere the plies together, the pocket-forming means preventing the adjacent plies in said zone from adhering together; removing the ball from the mold and cutting a slit in said zone through the adhered outer plies to said anvil; removing the anvil; punching a row of holes on each side of the slit; and inserting a lace through the holes to draw the sides of the slit together.

4. The method of forming an inflated ball having a bladder provided with a valve, the steps of forming a patch with a fabric base having adhesive thereon, a layer of polyethylene overlying one face of the base and terminating inwardly of the edges thereof, and a thin metal anvil overlying the polyethylene and terminating inwardly of the edge thereof; laying on the bladder a plurality of panels of fabric having adhesive thereon and said patch to form a multiply casing therearound with the patch located at a zone remote from said valve; enclosing the casing in a layer of rubber; placing the ball in a mold and subjecting the ball to heat and pressure to adhere the plies and layer of rubber together and to form the required surface configuration on the rubber layer, the polyethylene and metal anvil plate preventing the adjacent plies in said zone from adhering together; removing the ball from the mold and cutting a slit in said zone only through the adhered outer plies and layer of rubber; removing the anvil; punching a row of holes in the outer plies on each side of the slit; and inserting a lace through the holes to draw the sides of the slit together.

5. The method of forming an inflated ball having a bladder provided with a valve, the steps of forming a casing around said bladder by laying on the bladder two fabric plies comprising a plurality of panels of fabric having adhesive thereon; laying on these plies, intermediate the edges of one of the panels at a zone remote from said valve, a pocket-forming patch including a fabric layer having adhesive thereon, an adhesion resistant layer on one face within the edges of the fabric layer and an anvil plate within the edges of the adhesion resistant layer; laying on at least one more outer ply of panels of fabric having adhesive thereon, laying on a layer of rubber sheeting; placing the ball in a mold and subjecting the ball to heat and pressure to adhere together the plies, patch and the rubber layer, the adhesion resistant layer and anvil preventing the patch and adjacent ply in said zone from adhering together; removing the ball from the mold and cutting a slit in said zone through the adhered outer plies and rubber layer to said anvil; removing the anvil; punching a row of holes in said outer plies and rubber layer on each side of the slit; and inserting a lace through the holes to draw the sides of the slit together.

6. The method of forming an inflated ball having a bladder provided with a valve, the steps of forming a multiply casing around said bladder by laying on the bladder, at a zone remote from said valve, a pocket-forming patch including a fabric layer engaging the bladder and having adhesive thereon, an adhesion resistant layer on the exposed face within the edges of the fabric layer and an anvil plate within the edges of the adhesion resistant layer, laying on a plurality of outer plies of panels of fabric having adhesive thereon with the patch located within the overlying panels; laying on a layer of rubber sheeting; placing the ball in a mold and subjecting the ball to heat and pressure to adhere together the plies and the rubber layer, the adhesion resistant layer and anvil preventing the overlying ply in said zone from adhering to said patch; removing the ball from the mold and cutting a slit in said zone through the adhered outer plies and rubber to said anvil; removing the anvil; punching a row of holes in said outer plies and rubber on each side of the slit; and inserting a lace through the holes to draw the sides of the slit together.
